US0D1098666S

(12) **United States Design Patent** (10) Patent No.: **US D1,098,666 S**
(45) Date of Patent: ** Oct. 14, 2025

(54) **USER INTERFACE FOR CPAP DEVICE**

(71) Applicant: **KONINKLIJKE PHILIPS N.V.**,
Eindhoven (NL)

(72) Inventor: **Stephan Daniel Morgan**, North
Huntingdon, PA (US)

(73) Assignee: **KONINKLIJKE PHILIPS N.V.**,
Eindhoven (NL)

(**) Term: **15 Years**

(21) Appl. No.: **29/800,649**

(22) Filed: **Jul. 22, 2021**

(51) LOC (15) Cl. **24-01**

(52) U.S. Cl.

USPC **D24/107**

(58) **Field of Classification Search**

Assistant Examiner — Darmawan Truong

(57) **CLAIM**

The ornamental design for a user interface for cpap device as shown and described.

DESCRIPTION

FIG. 1 is a front view showing a first embodiment of a user interface for cpap device;

FIG. 2 is a front view showing a second embodiment of a user interface for cpap device; and,

FIG. 3 is a front view showing a third embodiment of a user interface for cpap device.

The dash-dot-dash lines shown in the drawings represent boundaries of the claimed design and form no part of the claimed design.

1 Claim, 3 Drawing Sheets
